UNITED STATES PATENT OFFICE

THOMAS JAMES FLANAGAN, OF TULSA, OKLAHOMA, ASSIGNOR TO GASO PUMP AND BURNER MANUFACTURING COMPANY, OF TULSA, OKLAHOMA, A CORPORATION OF OKLAHOMA

PUMP

Application filed January 11, 1927. Serial No. 160,489.

My invention relates to new and useful improvements in pumps and more particularly to a double acting duplex power pump, the principal object of the invention residing in the provision of a worm drive for a pump of this character whereby the number of gears formerly used in said pumps may be greatly reduced.

Another object of the invention resides in forming the cross head cylinder and the lower half of the combined crank case and gear housing of a single casting and providing integral bearing portions, for the crank shaft, on the lower half of the combined crank case and gear housing.

A further object consists in forming the crank shaft, intermediate its ends, with a relatively large flange to which a ring gear may be detachably connected, it being understood that all of the gears, as well as other working parts operate in an oil bath within the combined crank case and gear housing, the teeth of the ring gear acting as buckets to carry the oil upwardly to be further distributed, by splashers, to all working parts of the pump.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a top plan with a portion of the upper half of the combined crank case and gear housing broken away.

Fig. 2 is a side elevation with a part of the upper half of the combined crank case and gear housing broken away.

Fig. 3 is a longitudinal vertical section through the cross head cylinder and combined crank case and gear housing with parts shown in side elevation.

Fig. 4 is an end view of the crank shaft with its associated flange, and

Fig. 5 is a longitudinal vertical section through the crank shaft, flange, and ring gear.

In the drawings 1 indicates a base adjacent one end of which is supported the pump cylinders 2 of well-known construction and adjacent the opposite end of which is supported an electric motor 3 having the shaft 4 projecting from one end thereof. Supported on the base 1, between the pump cylinders and electric motor, is the combined crank case and gear housing. This combined case and housing includes the lower half or section 5 and the upper half or cap 6, the upper half being secured to the lower half by means of the bolts 7 or other suitable fastenings. The lower half 5 at the bottom is formed with the well or depressed portion 8 and aligned openings 9 and 10 communicate with the well, from opposite sides, as shown more particularly in Fig. 3 of the drawings. Formed integral with the lower half of the case or housing are a pair of parallel cylinders 11 in each of which operates a cross head 12 as shown more particularly in Fig. 3.

Secured to each of the cross heads 12 is one end of a piston rod 13 the opposite end being connected to a piston operable in the pump cylinders 2. The piston rods 13 operate through stuffing boxes 14 secured to the ends of the cylinders 11.

Bearings 15 are formed integrally with the combined crank case and gear housing and support the ends of the crank shaft 16 having the crank portions 17 and 18 set at a 90° angle. Bearing plates 19 are placed over the upper surface of the crank shaft, adjacent each end, and are secured to the bearings 15 by means of the bolts 20 or other suitable fastenings. Connecting rods 21 are connected to the crank portions 17 and 18 and to the cross heads 12 operable in the cylinders 11. A relatively large flange 22 is formed integrally with the crank shaft 16, between the crank portions 17 and 18, and has at one side edge an outwardly extending portion or lip 23 as shown more particularly in Fig. 4.

5 of the drawings. A ring gear 24 is received upon the flange 22 and engages the extension or lip 23 to which it is secured by means of the bolts 25 or other suitable fastenings. The heads 26 of the bolts 25 are provided with transversely extending openings and wire 27 is passed through these openings with its ends connected at the point 28. This wire serves to hold the bolts against 10 accidental displacement.

A shaft 29 extends through the opening 10 adjacent the bottom of the crank case and gear housing and is supported by the ball-bearings 30 and 31. A plate 32 is secured to 15 the casing or housing by means of the bolts 33, forms a closure for the opening 10 and holds the ballbearings 31 in position. The end of the shaft 29 passes through the stuffing box 34 and is connected to the shaft 4 of the 20 electric motor 3 by means of the coupling 35. A cap or plate 36 is secured to the casing or housing by means of the bolts 37 and forms a closure for the opening 9. Access may be gained to the end of the shaft 29 and its supporting bearing by removing the plate or cap 36. A worm gear 38 is carried by the 25 shaft 29 and meshes with the ring gear 24.

From the above detailed description it is thought that the construction of my pump 30 will be clearly understood as well as the mode of operation. The electric motor 3 will drive the shafts 4 and 29 and through means of the gears 38 and 24 rotate the crank shaft 16 which through means of the connecting rods 35 21 reciprocate the cross heads 12, the piston rods 13, and the pistons within the cylinders 2. By providing the worm gear drive I employ the minimum number of gears possible and do away with a great many gears now 40 ordinarily used in a pump of the character described. At the same time the ring gear 24 is secured to the crank shaft in a novel manner and the crank shaft is supported by the bearings which are forced integral with 45 the lower half of the combined crank case and gear housing. Oil is placed in the crank case and gear housing and all parts contained therein operate in an oil bath. The teeth of the gear 24 act as buckets in carrying oil to 50 the top of the crank case and gear housing where it is distributed by splashes to all working parts of the pump.

Having fully described my invention what I claim as new and desire to secure by Letters 55 Patent is:

1. A pump of the character described including a combined crank case and gear housing having a cylinder formed integral therewith, said crank case and gear housing having an opening providing side portions having bearings formed on the upper surface thereof and positioned inwardly of the outer surfaces, said bearings being open at the top, a crank shaft removably and rotatably supported in the bearings with its ends covered

by the sides of the case and housing, bearing plates detachably connected to said side portions and overlying the shaft within the sides, a gear carried by the shaft, a cover detachably connected to the crank case and gear housing for closing the opening therein and enclosing the gear, the bearings and bearing plates, and means engageable with the gear for rotating the shaft.

2. A pump of the character described including a combined crank case and gear housing having a cylinder formed integral therewith, said crank case and gear housing being open at the top forming sides with bearings on the upper edges and a well being formed in the bottom with openings at opposite ends extending to the exterior of the case or housing, a crank shaft removably supported in the bearings at the upper edges of the sides, a gear carried by the shaft, a second shaft extending longitudinally of the openings at the ends of the well in the case or housing, a gear carried by said second mentioned shaft and in mesh with the gear carried by the first mentioned shaft, said gear carried by the second mentioned shaft being positioned in the well, a cover detachably connected to the case and housing for closing the opening, and means for rotating the second mentioned shaft.

In testimony wherof I hereunto affix my signature.

THOMAS JAMES FLANAGAN.
